UNITED STATES PATENT OFFICE

HUBERT H. FLIEGEL, OF MERRICK, NEW YORK

HATCH CONSTRUCTION FOR UPPER DECKS

Application filed January 5, 1932. Serial No. 584,876.

This invention relates generally to ships' hatches, and refers more particularly to an upper deck hatch construction which is in the nature of an improvement upon my prior 5 United States Letters Patent No. 1,835,856, granted December 8, 1931.

In addition to attaining the general objects and advantages set forth in the previous patent above referred to, the present 10 invention aims to simplify the means for supporting the hatch cover sections from the deck for shifting movement to and from covering and uncovering relations with respect to the hatchway and for raising and lowering 15 the cover sections.

The invention further resides in the provision of an improved packing and sealing means for rendering the hatch watertight without resorting to the use of tarpaulins.

With these and other objects in mind, reference is made to the following specification and accompanying drawings, in which there is disclosed by way of example a single and preferred embodiment of the invention, while the appended claims define the actual scope thereof.

In the drawings:

Figure 1 is a side view illustrating the hatch in closed condition.

Figure 2 is a similar view illustrating the hatch cover sections raised with reference to the coaming preparatory to the shifting of the sections to uncovering relation to the hatchway.

Figure 3 is an enlarged transverse sectional view taken approximately on the line indicated at 3-3 in Figure 1.

Figure 4 is a fragmentary side view illustrating one way in which the cover sections may be stowed when the hatch is opened.

Figure 5 is a fragmentary enlarged longitudinal sectional view illustrating in full and broken lines the raised and lowered condition of the hatch cover.

Figure 6 is a fragmentary transverse sectional view taken approximately on the line 6-6 of Figure 5.

Figure 7 is a fragmentary enlarged sectional view illustrating in detail the im-

proved form of the packing for sealing the hatchway.

Referring to the drawings by characters of reference, A designates the top or shelter deck of a vessel formed with an opening or 55 hatchway B having an upstanding or raised coaming C, preferably of steel. The upper marginal edge of the coaming in the present instance is provided with upwardly divergent inner and outer flanges 10 and 11 which define a substantially V-shaped continuous channel 12 for the reception of a packing or gasket 13, which is preferably of rubber. The inner confronting faces of the flanges 10 and 11 adjacent the upper edges are 60 formed with moulding strips 14 which are preferably half round and which are spaced from each other so as to receive therebetween and therebelow the packing or gasket 13.

The hatch construction includes one or 70 more covers, depending upon its size, but in the present instance, the hatch includes two cover sections designated generally by the reference characters D and E, which sections are of identical construction and which include a top panel 15 of greater width and greater length than the upper margin of the coaming so as to provide an overhang. The under side of the panel 5 is formed with a continuous side and end moulding 16, preferably of half round construction in cross section, which is designed to cooperate with the packed upper marginal edge of the coaming C, as clearly illustrated in Figures 3 75 and 7 of the drawings. This affords an effective means for sealing the hatch when closed by the cover to render the same watertight without resorting to the use of tarpaulins.

The protruding or overhanging side edges 17 of the hatch cover panels 15 are formed with an inner longitudinally extending angle strip 18 and with an outer inverted longitudinally extending channel strip 19 which incidentally serve to strengthen the 80 cover structure but which primarily constitute bearing means for depending supporting legs 20. The legs 20 in horizontal cross section are preferably channel shaped, with the webs cut away adjacent the upper and lower ends so as to define by the protruding

upper and lower portions 21 and 22 of the flanges, bifurcated parts. The upper furcations 21 receive therethrough a fulcrum bolt or pin 23 which extends through the depending flanges 24 of the channel 19 and through the depending flange 25 of the angle strip 18. Each leg 20 is provided with a lateral strut or brace 26 which is secured to the inner side thereof intermediate its height, and which 5 provides means for engaging with the innermost leg, the hook 41 at the terminal of a cable 42 which is designed to be trained over a sheave 43 and thence connected with suitable tackle for exerting an inward pull on each of the innermost legs to straighten the 70 same for raising the hatch covers or for permitting the angular movement of the legs to lower the hatch cover sections. The pulley or sheave 43 may be supported in any desired 75 manner, either from the deck, the rails or the sides of the coaming and, obviously, there will be a cable 42 for each side of each hatch cover section.

10 brace extends upwardly and inwardly with the upper extremity receiving therethrough the fulcrum bolt or pin 23. The spacing sleeve 27 surrounds the fulcrum bolt or pin 23 and is interposed between the upper 15 terminal of the brace or strut 26 and the inner side flange 24 of the channel 19. This affords a wide fulcrum bearing for the upper end of the leg, making the supporting leg more stable and rigid laterally. The lower fur- 20 cations 22 receive therebetween a peripheral- 25 ly grooved wheel or roller 28 which is de- 30 signed to embracingly engage a rail 29 on the deck B, it being understood that one rail is disposed on each side of the hatchway 35 coaming C, as illustrated in Figure 3 of the drawings. Each leg 20 is of an appropriate length when disposed perpendicular to the deck, to position the hatchway above and clear of the coaming, whereby the covers may 40 be rolled on the rails to and from their covering relation to the coaming. In order to limit the swinging of the legs and to afford a definite stop where the same will be perpendicular to the horizontal plane of the 45 hatch covers and deck B, the upper furcations 21 are provided with a flat 30 at right angles or perpendicular to the vertical free edge of the flanges of the legs. The flat 30 merges into a curved or arcuate portion 31 50 which is struck on a radius from the axial center of the fulcrum pin 23. This arrangement therefore permits the legs to be swung to an angular position with reference to the horizontal plane of the hatch covers and 55 deck B, as illustrated in Figure 1 and in broken lines in Figure 5 of the drawings. It thus follows that when the hatch covers are 60 located over the coaming, the legs when released will permit the covers to gravitate to a lowered seated position on the upper edge 65 of the coaming.

As illustrated, each hatch cover D and E is provided with a plurality of legs 20 disposed on each side thereof and depending 55 therefrom. The lower ends of the legs are connected by a link 35 to cause the legs on one side of each hatch cover to move in unison. Said links are preferably in the nature of rods, the opposite ends of which are 60 threaded as at 36 to threadedly engage in yokes 37 which are fulcrumed on the roller shafts or trunnions 38.

65 The yoke 37 of the innermost leg is provided with inwardly directed extensions 39 spaced apart and traversed by a pin 40. This

provides means for engaging with the innermost leg, the hook 41 at the terminal of a cable 42 which is designed to be trained over a sheave 43 and thence connected with suitable tackle for exerting an inward pull on each of the innermost legs to straighten the same for raising the hatch covers or for permitting the angular movement of the legs to lower the hatch cover sections. The pulley or sheave 43 may be supported in any desired 70 manner, either from the deck, the rails or the sides of the coaming and, obviously, there will be a cable 42 for each side of each hatch cover section.

In order to hold the legs in their vertical 80 or perpendicular position to support the hatch cover sections elevated after they have been initially raised by the cables 42 and tackle, retaining bars 45 are employed for each of the innermost legs 20 of each hatch 85 cover section, and said retaining bars are preferably provided with upper and lower bifurcated terminals 46 and 47. The upper 90 bifurcations 46 are disposed between the depending flanges 24 of the channels 19 and are fulcrumed thereto by means of pins 48 which 95 may be permanently or removably installed. The lower bifurcations of each retaining bar are designed to be received between the flanges of the channel shaped legs 20 and are 100 apertured to receive the removable retaining pins 49 which may be locked in position by a cotter pin 50 and which are preferably anchored by chains 51 to the legs to avoid their 105 loss and misplacement. It is, of course, understood that the flanges of the leg are correspondingly apertured and, if desired, each leg may be provided with an upper set of 110 apertures 52 with which the lower bifurcations 47 of the retaining bars may register to receive the retaining pins 49 when the hatch covers are lowered, thus serving to lock the hatch covers in their lowered seated position on the coaming.

Obviously, the hatch covers when not in use 115 may be stowed in any desired manner but, as illustrated in Figure 4 of the drawings, pairs of longitudinally spaced upstanding holders 55 and 56 may be provided adjacent one end of the coaming, which holders may form a part of the track rails 29 as illustrated, or otherwise. One hatch cover section may be received between each pair of holders 55 and 56 and the other between the holder 56 and the end of the coaming C. The innermost 120 holders 56 may be provided with a pivoted upper end 57 which is swung downwardly to the dotted line position illustrated in Figure 4 until after the first hatch cover section has been stowed. After the first hatch cover section is stowed, the legs will be swung downwardly to the position illustrated in Figure 4, after which the terminals 57 will be swung upwardly and the second hatch cover section 125 stowed and its legs swung upwardly to the 130

position illustrated in Figure 4. In practice, however, it is obvious that the hatch cover sections may be otherwise stowed, the illustration in Figure 4 merely showing one of the possibilities.

5 From the foregoing, it will thus be seen that a hatch for upper decks has been devised in which the cover or cover sections are supported from the deck when not in active use, whereby the same may be rolled to and from a stowed position, together with a means for sealing the covers against the entrance of water without the use of tarpaulins.

10 While a preferred embodiment of the invention has been illustrated, it is to be understood that variations and modifications which fall within the scope of the claims may be resorted to when desired.

What is claimed is:

20 1. In a deck hatch construction, a hatchway having a coaming, a hatch cover and legs provided at the lower ends with wheels, said legs having swingable connection to and depending from the opposite sides of the hatch cover and of a length when disposed perpendicular to the hatch cover to elevate said cover above and clear of the coaming to permit of rolling of the same to and from a stowed position clear of the hatchway.

30 2. In a deck hatch construction, a hatchway having a coaming, a track including parallel rails extending along opposite sides of the coaming, a hatch cover, legs provided at the lower ends with track engaging wheels, swingably connected to and depending from the opposite sides of the hatch cover and of a length when disposed perpendicular to the hatch cover, to elevate the hatch cover above and clear of the coaming to permit of the 40 rolling of the same over the track to and from a stowed position clear of the hatchway.

35 3. In a hatch construction, a hatchway having a coaming, a track including parallel rails extending along opposite sides of the coaming, a hatch cover, a plurality of legs swingably connected to, depending from the sides of the hatch cover and provided at their lower ends with track engaging wheels, said legs being of a length when disposed perpendicular to the hatch cover, to elevate the same above and clear of the coaming to permit rolling thereof to and from a stowed position clear of the hatchway.

45 4. In a hatch construction, a hatchway having a coaming, a track including parallel rails extending along opposite sides of the coaming, a hatch cover, a plurality of legs swingably connected to, depending from the sides of the hatch cover and provided at their lower ends with track engaging wheels, said legs being of a length when disposed perpendicular to the hatch cover, to elevate the same above and clear of the coaming to permit rolling thereof to and from a stowed position clear of the hatchway and means for releas-

ably locking said legs in a perpendicular or angular position.

5. In a deck hatch construction, a hatchway having a coaming, a hatch cover adapted for watertight seating on the upper edge of the 70 coaming and means for supporting the hatch cover from the deck for rolling movement to and from its covering relation to the coaming, said means including legs having wheels at the lower ends, said legs being fulcrumed to 75 and depending from opposite sides of the hatch cover for swinging movement respectively to angular and perpendicular relation to the hatch cover to respectively lower the hatch cover to seated relation on the coaming 80 and to elevate the same clear of the coaming for rolling movement over the deck.

6. In a deck hatch construction, a hatchway having a coaming, a hatch cover adapted for watertight seating on the upper edge of the 85 coaming and means for supporting the hatch cover from the deck for rolling movement to and from its covering relation to the coaming, said means including legs having wheels at the lower ends, said legs being fulcrumed to 90 and depending from opposite sides of the hatch cover for swinging movement respectively to angular and perpendicular relation to the hatch cover to respectively lower the hatch cover to seated relation on the coaming 95 and to elevate the same clear of the coaming for rolling movement over the deck.

7. In a deck hatch construction, a hatchway having a coaming raised above the deck, a hatchway cover adapted to fit thereover and of greater width than the coaming, a plurality of legs carried by the opposite sides of the cover and fulcrumed thereto for swinging movement to an angular relation for permitting the hatch cover to interfit with the coaming, said legs being of an appropriate length when swung to a perpendicular relation to the hatch cover, to elevate and disengage the same from the coaming and to support the same from the deck for rolling movement to and from a covered relation to the coaming.

8. The combination with a deck formed with a hatchway having a coaming and a hatch cover having depending means adapted to vertically interfit with the coaming, of a plurality of legs carried by opposite sides of the hatch cover and swingable with reference thereto to constitute a common means for elevating the hatch cover to disengage the same from the coaming and for supporting the hatch cover for rolling movement over the deck when so elevated.

9. The combination with a deck formed with a hatchway having a coaming and a hatch cover having depending means adapted to vertically interfit with the coaming, of a plurality of legs carried by opposite sides of 130

the hatch cover and swingable with reference thereto to constitute a common means for elevating the hatch cover to disengage the same from the coaming and for supporting the hatch cover for rolling movement over the deck when so elevated and releasable means for locking the legs in predetermined relatively swung positions with reference to the hatch cover.

10. The combination with a deck formed with a hatchway having a coaming and a hatch cover having depending means adapted to vertically interfit with the coaming, of a plurality of linked legs carried by opposite sides of the hatch cover and swingable with reference thereto to constitute a common means for elevating the hatch cover to disengage the same from the coaming and for supporting the hatch cover for rolling movement over the deck when so elevated.

11. A deck hatch cover having depending means adapted to vertically engage with a hatchway coaming when seated thereon and legs carried by opposite sides of the hatch cover, fulcrumed thereto and depending therefrom and constituting a common means for engaging the deck to lower and raise the hatch cover whereby to engage when lowered said depending means with and to disengage the same when raised from the coaming and to support the hatch cover for rolling movement over the deck when raised.

12. A deck hatch cover having depending means adapted to vertically engage with a hatchway coaming when seated thereon and legs carried by opposite sides of the hatch cover, fulcrumed thereto and depending therefrom and constituting a common means for engaging the deck to lower and raise the hatch cover whereby to engage when lowered said depending means with and to disengage the same when raised from the coaming and to support the hatch cover for rolling movement over the deck when raised and means for locking said legs against movement when swung to a position to elevate the cover.

13. The combination with a deck formed with a hatchway having a coaming and a hatch cover having depending means adapted to vertically interfit with the coaming, of a plurality of linked legs carried by opposite sides of the hatch cover and swingable with reference thereto to constitute a common means for elevating the hatch cover to disengage the same from the coaming and for supporting the hatch cover for rolling movement over the deck when so elevated and guide means located adjacent the hatchway for training hoisting tackle therearound for connection with the legs to exert a pull thereon for effecting swinging movement thereof to raise the hatch cover.

14. A deck hatch cover having depending means adapted to vertically engage with a hatchway coaming when seated thereon and

a plurality of linked legs carried by opposite sides of the hatch cover, fulcrumed thereto and depending therefrom and constituting a common means for engaging the deck to lower and raise the hatch cover whereby to engage when lowered said depending means with and to disengage the same when raised from the coaming and to support the hatch cover for rolling movement over the deck when raised.

15. The combination of a deck formed with a hatchway having a coaming raised above the deck, of a hatch cover having depending means adapted to engage with the coaming when seated thereon and means carried by the hatch cover engageable with the deck for lowering and raising the hatch cover into and out of engagement with the coaming and for supporting the hatch cover from the deck when so raised to permit of rolling the same over the deck, said latter means comprising a plurality of legs pivotally carried by the opposite sides of the hatch cover for swinging movement in one direction to and from a perpendicular relation to the hatch cover.

16. The combination of a deck formed with a hatchway having a coaming raised above the deck, of a hatch cover having depending means adapted to engage with the coaming when seated thereon and means carried by the hatch cover engageable with the deck for lowering and raising the hatch cover into and out of engagement with the coaming and for supporting the hatch cover from the deck when so raised to permit of rolling the same over the deck, said latter means comprising a plurality of legs pivotally carried by the opposite sides of the hatch cover for swinging movement in one direction to and from a perpendicular relation to the hatch cover and a linked connection between the legs of each side of the hatch cover to effect swinging movement of the same in unison.

17. In combination, a hatch cover having a depending arcuate sealing strip and a hatchway coaming having upwardly divergent flanges at its upper edge defining a substantially V-shaped groove and spaced arcuate confronting beads adjacent the upper edges of the inner sides of said flanges.

18. In combination, a hatch cover having a depending arcuate sealing strip and at hatchway coaming having upwardly divergent flanges at its upper edge defining a substantially V-shaped groove and spaced arcuate confronting beads adjacent the upper edges of the inner sides of said flanges and a resilient packing within the groove disposed below and between the flanged beads.
